(57) **CLAIM**

I claim the ornamental design for a wood pinching wedge, as shown and described.

DESCRIPTION

FIG. 1 is a perspective view of a wood pinching wedge, showing a first embodiment of my new design;

FIG. 2 is a bottom plan view of FIG. 1;

FIG. 3 is a top plan view of FIG. 1;

FIG. 4 is a left-side elevational view of FIG. 1, the right-side elevational view being a mirror image thereof;

FIG. 5 is a front elevational view of FIG. 1;

FIG. 6 is a rear elevational view of FIG. 1;

FIG. 7 is a perspective view of a second embodiment thereof;

FIG. 8 is a bottom plan view of FIG. 7;

FIG. 9 is a top plan view of FIG. 7;

FIG. 10 is a left-side elevational view of FIG. 7, the right-side elevational view being a mirror image thereof;

FIG. 11 is a front elevational view of FIG. 7; and

FIG. 12 is a rear elevational view of FIG. 7.

FIG. 13 is a perspective view of a third embodiment thereof;

FIG. 14 is a bottom plan view of FIG. 13;

FIG. 15 is a top plan view of FIG. 13;

FIG. 16 is a left-side elevational view of FIG. 13, the right-side elevational view being a mirror image thereof;

FIG. 17 is a front elevational view of FIG. 13; and,

FIG. 18 is a rear elevational view of FIG. 13.
